ELASTIC FABRIC

Filed Jan. 4, 1936

FIG. 1.

FIG. 2.

FIG. 3.

INVENTOR:

Clarence D. Maurer,

BY *Alfred E. Schinger,*
ATTORNEY.

UNITED STATES PATENT OFFICE

98,729

DESIGN FOR ELASTIC FABRIC

Clarence D. Maurer, West Reading, Pa., assignor
to The Narrow Fabric Company, West Reading,
Pa., a corporation of Pennsylvania

Application January 4, 1936, Serial No. 60,411

Term of patent 14 years

To all whom it may concern:

Be it known that I, Clarence D. Maurer, a citizen of the United States of America, residing at West Reading, in the county of Berks and State of Pennsylvania, have invented a new, original, and ornamental Design for an Elastic Fabric, of which the following is a specification, reference being had to the accompanying drawing, forming part thereof.

Figure 1 discloses a portion of elastic fabric embodying my ornamental design, and to which no tension has been applied.

Fig. 2 discloses a portion of the elastic fabric depicted in Fig. 1, as it appears when subjected to tension substantially equivalent to that incident to normal use.

Fig. 3 discloses the reverse side of the portion of elastic fabric depicted in Fig. 1, and to which no tension has been applied.

The figures disclose the elastic fabric enlarged to approximately one and one-half times normal size, so that they will be approximately full size upon the reduction of the same to the ultimate size as appearing in the patent copy.

I claim:

The ornamental design for elastic fabric, as shown and described.

In testimony whereof I affix my signature.

CLARENCE D. MAURER.
